(57) **CLAIM**

The ornamental design for an expandable medical device, as shown and described.

DESCRIPTION

FIG. 1 is a perspective view of an expandable medical device showing our new design, with the expandable medical device in an unexpanded state;

FIG. 2 is a first side elevational view of the expandable medical device in the unexpanded state;

FIG. 3 is a second side elevational view of the expandable medical device in the unexpanded state;

FIG. 4 is a third side elevational view of the expandable medical device in the unexpanded state;

FIG. 5 is a fourth side elevational view of the expandable medical device in the unexpanded state;

FIG. 6 is a distal end view of the expandable medical device in the unexpanded state;

FIG. 7 is a proximal end view of the expandable medical device in the unexpanded state;

FIG. 8 is first side elevational view showing our new design, with the expandable medical device in an expanded state;

FIG. 9 is a second side elevational view of the expandable medical device in the expanded state;

FIG. 10 is a third side elevational view of the expandable medical device in the expanded state; and,

FIG. 11 is a fourth side elevational view of the expandable medical device in the expanded state.

The broken lines illustrate unclaimed features and form no part of the claimed design.
